UNITED STATES PATENT OFFICE.

DANIEL W. PAIGE, OF SANFORD, MAINE.

IRONING-TABLE.

SPECIFICATION forming part of Letters Patent No. 688,880, dated December 17, 1901.

Application filed May 3, 1901. Serial No. 58,606. (No model.)

To all whom it may concern:

Be it known that I, DANIEL W. PAIGE, a citizen of the United States, residing at Sanford, in the county of York and State of Maine, have 5 invented certain new and useful Improvements in Ironing-Tables, of which the following is a specification.

My invention relates to ironing-tables, and has for its objects to provide an ironing-table 10 that is inexpensive in construction, easy to operate, that has means for securing the ironing-table to an ordinary table or other support, and that when not in use takes up but a minimum amount of space. I attain these objects by the mechanism illustrated in the accompanying drawings, in which—

Figure 1 is a side view in elevation of my invention in operative position, partly in section; Fig. 2, a bottom plan view of the iron- 20 ing-table with the parts folded; Fig. 3, a bottom plan view of the sleeve-board; Fig. 4, an end view of the sleeve-board.

In the drawings, in which similar letters of reference denote like parts throughout the 25 several views, A represents the ironing-board of my ironing-table, of ordinary shape, and B a sleeve-board that may be fixed on the ironing-board A by the means hereinafter described.

On the bottom of the ironing-board A a leg 30 C is pivoted by means of the brackets D, fixed to the ironing-board A by any suitable means, to which are pivoted the links E, which are in turn pivoted to the leg C. The purpose of 35 this construction is to permit of the leg C, when the board is not in use, lying close to the ironing-board A, and thus taking up the least amount of space.

Near the end of the ironing-board A an angular plate F is suspended by a pin G, passing 40 through an aperture H in said ironing-board A. The angle-plate F consists of a horizontally-disposed portion f and a portion f', forming an obtuse angle to the portion f. The purpose of this construction is that when 45 the device is in an operative position the part f fits under the edge of a table or shelf I, while the part f' bears against the under edge of the leg C and holds it in a supporting position by means of the lug f'', formed by turning the part f' at right angles, fitting into the 50 transverse slot c in the leg C. Pivoted to the

upper end of the pin G is a cam-lever K, bearing against a metal plate L, set in the top of the ironing-board A, the cam-face k of the 55 lever K terminating with a flat face k'. M is a strip of felt or other non-abrading material to prevent injury to the top of the table I when the board is in use. By this construction it will be readily seen that the same 60 clamping device serves to hold the ironing-board A fixed to the table or shelf I and the leg C in a supporting position.

On the bottom of the sleeve-board B is fixed a cross-shaped plate N, to which in turn is fixed 65 a slanting arm O, at the end of which are fixed jaws P, designed to embrace the top and bottom of the ironing-board A or any other support to hold the sleeve-board B in operative position.

The operation is as follows: Lower the leg 70 C, place lug f'' in the slot c, and, holding the part f' of the angle-iron F against the leg C, push the board onto the edge of a table or shelf I. Then turn the lever K over until the 75 flat face k' rests on the top of the board, and the device is in an operative position.

The sleeve-board B is attached to the ironing-board A by means of the jaws P, the ironing-board A being clamped between them. 80

Having thus described my invention, what I claim is—

1. In an ironing-table, an ironing-board, a pin loosely mounted in an aperture thereof, a plate mounted thereon having a horizontal 85 portion, a portion adapted to fit the side of a leg pivoted to said ironing-board and a lug to fit in a slot in said leg, and means attached to the upper end of said pin for raising said plate, substantially as shown and described. 90

2. In an ironing-table, an ironing-board, a pin loosely mounted in an aperture thereof, a plate mounted thereon having a horizontal portion and a portion adapted to fit the side of a leg pivoted to said ironing-board, having 95 its end turned up to form a lug adapted to fit in a slot in said leg, and a lever pivoted to the upper end of said pin having a cam-face bearing against the top of said ironing-board, substantially as shown and described. 100

3. In an ironing-table, an ironing-board, a leg pivoted thereto by means of links and brackets, a transverse slot in said leg, an angular plate suspended by means of a pin pass-

ing through the ironing-board, said angular plate having a horizontally-disposed portion and a portion at an obtuse angle thereto, a lug on the end of said angular plate adapted 5 to fit in the slot in said leg, and a lever on the end of said pin having a cam-face and a flat face, substantially as shown and described.

In testimony whereof I hereto affix my signature in the presence of two witnesses.

DANIEL W. PAIGE.
